Inventor:

Eduard W. Brettell

United States Patent Office.

EDWARD W. BRETELL, OF NEWARK, NEW JERSEY.

Letters Patent No. 66,940, dated July 23, 1867.

IMPROVEMENT IN NIGHT-LATCHES.

The Schedule referred to in these Letters Patent and making part of the same.

TO ALL WHOM IT MAY CONCERN:

Be it known that I, EDWARD W. BRETELL, of the city of Newark, in the county of Essex, and State of New Jersey, have invented certain new and useful Improvements in Locks for Doors, etc.; and I do hereby declare that the following is a full and exact description thereof. The accompanying drawings form a part of this specification.

Figure 1 is a front view, with the plate removed to exhibit the interior, with the bolt thrown out.

Figure 2 is a horizontal view through the works and casing with the bolt thrown back.

Figure 3 is a front view, with the plate removed to exhibit the interior, with the bolt thrown back.

Figure 4 is a horizontal section through the cylinder, showing the sliding tumblers and their springs.

Figure 5 is a side view of the key, which is similar in its general form to those employed in several varieties of locks.

Figure 6 is a front and edge view of the frog-bridge.

Figure 7 is a front and edge view of the sliding tumblers.

Similar letters of reference indicate like parts in all the figures.

My invention is intended to make a lock more secure against "burglars," and little objectionable on account of cost.

To enable others skilled in the art to make and use my invention, I will proceed to describe its construction and operation by the aid of the drawings and of the letters of reference marked thereon.

Fig. 1, B is the casing; A is the bolt; C is the cylinder, cut or otherwise formed with a rectangular space in its interior for the sliding tumblers $\circ \circ^1 \circ^2 \circ^3$ to work in. D is a frog-bridge working on a pivot, the edge bearing against the sliding tumblers $\circ \circ^1 \circ^2 \circ^3$. S is a spring attached to the stop F and the bolt A for the purpose of keeping the bolt-stop in its proper place and holding the frog-bridge in its proper place also. Fig. 2, C* is an outside cylinder riveted to the front plate of the lock for the purpose of holding the inside cylinder C and slides $\circ \circ^1 \circ^2 \circ^3$ in their proper positions, with the aid of small springs at the bottom placed between the projecting arms; better shown in fig. 4. F is a stop for the purpose of holding the bolt back or keeping the same out, and is of construction similar to that employed in many other locks. A², as shown in fig. 2, is a thumb-piece used for drawing the bolt back without the use of a key. The frog-bridge D (shown in fig. 1 bearing on the dog y projecting out of the arm of the cylinder C) acts for throwing back the bolt and at the same time, when the key is inserted in slot e, fig. 2, will throw the sliding tumblers $\circ \circ^1 \circ^2 \circ^3$ in a proper position to allow frog-bridge D to enter (by turning the key) recesses of sliding tumblers $\circ \circ^1 \circ^2 \circ^3$, shown in fig. 4. O, of fig. 7, shows one of the sliding tumblers with the slot in its edge, in which the frog-bridge enters when in position to allow of same.

The operation of my lock will be readily understood. By inserting the proper key G into the thin key-hole e, fig. 2, and pushing down all the sliding tumblers $\circ \circ^1 \circ^2 \circ^3$ to their proper places and then turning the key the dog y will throw the frog-bridge D into the slots or recesses of the sliding tumblers $\circ \circ^1 \circ^2 \circ^3$, and at the dog y jumping off of the nose D* of the frog-bridge; then the arm of the cylinder C, fig. 4, holds the bolt back, and by letting the key loose the force of spring S, fig. 3, draws the bolt and frog-bridge and the other portions of the lock back into their proper positions; as shown in fig. 1.

Having now fully described my lock, what I claim as new, and desire to secure by Letters Patent, is as follows:

1. I claim the dog y on the cylinder arm of C, fig. 4, bearing on D*, shown in fig. 1, substantially in the manner and for the purpose herein set forth.

2. I claim the frog-bridge D, with its nose D*, as shown in fig. 6, substantially in the manner and for the purpose herein set forth.

EDWARD W. BRETELL.
